THE NORRIS PETERS CO., PHOTO-LITHO., WASHINGTON, D. C.

UNITED STATES PATENT OFFICE.

WILLIAM H. COX, OF VIRDEN, ILLINOIS.

SLIDING GATE.

SPECIFICATION forming part of Letters Patent No. 445,163, dated January 27, 1891.

Application filed July 5, 1890. Serial No. 357,855. (No model.)

To all whom it may concern:

Be it known that I, WILLIAM H. COX, a citizen of the United States, residing at Virden, in the county of Macoupin and State of Illinois, have invented certain new and useful Improvements in Sliding Gates; and I do hereby declare the following to be a full, clear, and exact description of the invention, such as will enable others skilled in the art to which it appertains to make and use the same.

My invention relates to an improvement in that class of sliding gates known as "lever openers," and more particularly in that species of such class in which a downward pull upon the free ends of the operating-levers acts both to open and to close the gate, and hence necessitates the provision of suitable reversing mechanism.

The object sought to be accomplished by my improved construction is to produce more sure, positive, and easily-operating reversing devices than have heretofore been known in the art, and also to effect an arrangement of parts whereby the gate is opened and closed in a more convenient manner than heretofore, and the exertion and labor in so doing greatly diminished.

A still further object is to provide an improved clutch or grip which will take a sure hold on the gate to move it in one direction and slide freely back to get a new purchase, and also one so constructed that the gate will run freely and smoothly through when opened directly by hand without the use of the operating-levers.

With these ends in view my invention consists in certain peculiarities of construction and combinations of parts, more fully described hereinafter, and pointed out in the claims.

Referring to the accompanying drawings, Figure 1 represents a side elevation of my gate shown in closed position, dotted lines representing its open position; Fig. 2, a similar view showing the parts in the position they assume when one of the levers is pulled down to open the gate and the front clutch is gripping the rail to throw back the latter; Fig. 3, a front end view with the gate open; Figs. 4, 5, and 6, detail views illustrating the mechanism for shifting the parts to reverse

the action of the lever, and Figs. 7 and 8 details of the clutch or grip.

In carrying out my invention I employ a suitable supporting frame or standard consisting of the upright posts 2 and 3 and the top and bottom cross-pieces 4 and 6, and along beside this frame slides the gate 7, which is of ordinary construction and operates on suitable grooved rollers 8, mounted on bearings 9 rigidly secured to and projecting from the posts 2 and 3, and is guided at its bottom by projections 9 from the bases of said posts.

Alongside one rail of the gate I arrange a supplemental strip 11, which extends the full length of the gate, and is set off slightly therefrom by means of blocks 12, inserted at suitable intervals, and this strip serves as a bar on which the clutches take hold to shift the gate. A pair of diverging vibrating levers 13 and 14 are pivoted independently of each other to the middle of the sill or bottom cross-piece 6 of the frame and extend to the supplemental strip 11. From their lower ends extend arms 15, rigidly secured to them and lying along the upper surface of the sill 6, forming with the parts 13 and 14 bell-crank levers, the office of which will be explained hereinafter. Short strips 16 are secured to the outside surfaces of the arms 15 and are fitted on the pivots of the levers to guide the latter in their movements and keep them in proper adjustment, and brace-rods 17 connect the arms of the bell-crank levers to strengthen them.

As before stated, the arms 13 and 14 of the bell-crank levers extend to the strip 11, and to their upper ends are connected the clutches or grips for taking hold on the gate to operate it. These clutches are constructed alike, and each consists of a pair of rectangular boxes or bands 18 and 19, surrounding the bar 11, and a connecting strip or arm 20. These bands or boxes are left open on their inner sides to allow of the passage of the blocks 12, and the arm 20 is rigid with the rear band 18 and pivotally connected to the forward one 19 by means of suitable lugs 21, projecting from the front side of the latter, corresponding lugs 22 on the arm fitting between said lugs 21 and a pivot-pin 23 extending transversely through all these lugs.

The bands 18 and 19 loosely surround the bar 11, and are connected to the lever 13 by a rod 24, pivoted at its opposite ends to the upper end of said lever and the center of the connecting-arm 20, respectively. Now it will be seen that upon drawing back the rod 24 the rear band 18 will slide on the bar 11, being rigidly secured to the arm 20; but the forward band 19 is pivotally connected to this arm at the center of its front side, and hence the rearward movement of the arm 20 will pull back this front side and throw forward the back portion of the band, thus causing the latter to bind upon the bar 11 and grip 15 the same as long as the draft is maintained on the rod 24. It is obvious that when this draft is removed the bar will slide freely back through the clutch; but it is also necessary that it should slide as freely forward through 20 it when closing the gate, and to this end I provide a stop 25, projecting from the post 2 and having a bifurcated end inclosing the strip 11, and on the top and bottom bars of the band 19 are formed lugs or projections 26, 25 which fit against said stop 25 when the clutch is in its normal position, and thus hold the band square and prevent it from binding on the bar 11 when the gate slides shut.

The opposite grip for closing the gate is 30 arranged similarly to the opening one, but of course is reversed, the rear band being the pivotal one and having projections fitting against a stop on the post 3. It will thus be evident that the strip will slide freely back 35 and forth through the two clutches in opening and closing the gate directly by hand without the use of the levers when the latter are in their normal positions, as shown in Fig. 1, with the horizontal arms of the bell-crank 40 levers resting on the sill 6. The free ends of these horizontal arms are pivotally attached to long rods 27 and 28, which converge toward their upper ends, crossing the levers 13 and 14 and extending up along the side of the 45 cross-piece 4, being confined and guided by a strip 29, secured along said cross-piece 4, but separated therefrom by blocks 30 at its opposite ends and middle. The blocks at the middle contain between them, and act as guides 50 for, a vertical sliding bar or strip 31, which extends down between the rods 27 and 28, being provided at its lower end with a stop 32 to prevent its accidental removal from between the strip 29 and cross-piece 4, and it is also provided on its upper end, above the ends of the rods 27 and 28, with a weight 33 to cause it to drop quickly when released from an elevated 55 position.

A plate 34 is fastened on the face of the bar 60 31, between the weight 33 and strip 29, and the sides of this plate project beyond the edges of the bar and are provided with recesses or depressions 35 of like form and similarly located. The preferred form of these 65 depressions is that of an oval aperture having an open front, so that the depression will form a socket below said opening, as seen

more clearly in Fig. 4. The upper ends of the rods 27 and 28 come in front of these openings, and they are bent at right angles to form 70 catches 36, arranged to drop into the depressions 35.

Back of the vertical bar 31 is secured a bolster 37, which is supported by the cross-piece 4 and a re-enforcing strip 5, and through this 75 bolster, at its center, extends transversely a short rock-shaft 38, on the forward end of which, between the strip 31 and the bolster, is rigidly fastened at its center a rocking arm or lever 39, on the opposite ends of which are 80 formed lugs or pins 40, projecting beneath the upper ends of the rods 27 and 28, respectively. The rear end of the rock-shaft 38 projects beyond the bolster, and on it is loosely mounted a shifting arm or vane 41, which operates in 85 a suitable chamber or depression made in said bolster and in the re-enforcing strip 5, and is confined on the rock-shaft by a linchpin 42. This linchpin is of considerable length and extends down along the surface of the vane 90 or arm between a pair of lugs 43, projecting from the latter. Hence it will be seen that the shifting of the vane will cause its lugs to strike the linchpin and thus turn the rock-shaft and the lever or arm on its outer end. 95

As previously stated, the projecting pins on the opposite ends of this rocking arm extend beneath the slanting rods 27 and 28, and it has also been set forth that the catches or bent ends of these rods come in front of the opening in the plate of the vertical sliding bar. Cross notches or depressions 44 are also made in the guide-strip 29 and cross-piece 4, into which the pins 40 drop and allow the rod-catches to fall into the depressions 35; but it 100 will be evident that while one pin has dropped into its slot and the rod is engaging the depression in the plate, the other end of the rocking lever will be elevated, and the pin on this end will thus be holding the end of the 105 other rod in raised position clear of the plate 34.

At the opposite ends of the gate on the top rail raised vertical pieces 45 are provided, and from their side faces project studs or pins 110 46, which are adapted to come in contact with the vane 41 to throw it back and forth.

The operating-levers and supports for the same are arranged as follows: The main post 2 extends above the gate high enough to support the cross-arm 10, which is arranged at right angles to said post and to the gate and is supported by the braces 47. The operating-levers consist of long rods 48, having their fulcrums on the opposite ends of the cross-arm 10 in suitable castings 49, removably fitting in sockets in said arm and confined by buttons 50. The lower ends of these rods are provided with eyes 51, which fit on the downwardly-bent hooks 52, secured in the upper 120 end of the vertical slide-bar 31 on the opposite sides of the same. It will thus be seen that the levers diverge, as they are fulcrumed on the ends of the arm-bar, and they are ex- 125 130

tended out over the middle of the roadway, being there provided with suitable depending cords 53 to be grasped in the hand and pulled down to operate the levers. The levers extend on an upward slant, as well as away from each other, so that a good purchase can be obtained for elevating the vertical slide-bar. Stops 54 are formed on the rods 27 and 28 to limit their movement, and hence 5 that of the levers, by coming in contact with the under side of the upper cross-piece 4. The gate itself is also provided with stops 55 at its opposite ends, which abut against the opposite ends of the re-enforcing piece 5 in 10 the back of the strip 4, and thus limit the movement of the gate.

The preferred construction of my device having been set forth, I will now proceed to describe its operation. The cords on the ends 15 of the levers depend over the center of the roadway, so that they can be readily manipulated without the necessity of driving to the side of the road, and upon pulling down upon either one or the other the inner or lower end 20 of the lever will of course be elevated and will pull up with it the vertical slide-bar 31. Now with the gate in the closed position shown in Fig. 1, the shifting-vane will be thrown forward, and consequently the forward lug on 25 the rocking bar 39 will have dropped into its depression in the guide-strip, and hence the catch on the end of the rod 27 will be engaging the front depression in the plate on the slide-bar, while the opposite end of said rocking bar will be in elevated position with its lug holding the rear rod 28 free of the plate and its depression. Therefore when the slide-bar is pulled up by the hand-lever, it carries 30 with it the rod 27, which, being connected to the free end of the lower arm of the front bell-crank lever, elevates said arm and throws back the lever 13. The upper end of this lever is connected to the clutch and the latter will grip the strip 11, as previously explained, 35 when the lever is thrown back and thus pull back the gate to the position shown in Fig. 2. The impetus given the latter by this action of the levers and clutch will carry it through the clutches and all the way open. In the 40 meantime, however, after the bell-crank lever has reached the limit of its stroke, the hand-lever is released and the weight of the upper end of the slide-bar causes it to drop quickly to its former position. The catch on the rod 45 45 is still contained within the depression of the plate, so that the bell-crank lever will be thrown forward to its initial position, while the clutch slides back on the bar; but as the gate reaches the limit of its rearward movement the pin 46 of the forward raised piece 50 55 60 65 70 75 80 85 90 95 100 105 110 115 120 125 130 135 140 145 150 155 160 165 170 175 180 185 rod 28 to drop into the opposite depression of the plate by reason of the pin 40 on its opposite end, which has been holding it free of the plate, dropping into the cross-notch 44. 70 Now a downward pull upon the opposite hand-lever (or upon the same lever) will cause the vertical slide-bar to pull up with it the rear rod 28, and thus actuate, through the medium of the rear bell-crank lever, the rear 75 clutch, which will grip the strip 11, and thus slide the gate shut in the same manner that the opposite clutch pulled it open. As the gate reaches its closed position the projection from the rear raised piece 45 strikes it again 80 and again throws it to the forward position, (shown in full lines in Fig. 1,) and the rocking bar is shifted, throwing the rod 28 clear of the plate and allowing the catch on the rod 27 to drop again into the depression on the 85 front side of said plate. If the pull on the hand-lever is not strong enough to throw the gate all the way open or closed, the slide-bar can be dropped and a new purchase of the clutch on the strip be secured, as the rod is 90 not thrown from engagement with the plate until the gate reaches full open and closed position. 95 It will be readily seen that the gate can be freely slid back and forth independent of the operating mechanism, if desired, without departing from the spirit and scope of my invention, and hence I do not wish to limit myself to the precise construction herein shown. 100 Having thus described my invention, what I claim as new, and desire to secure by Letters Patent, is— 110

1. The combination of the gate, a pair of vibrating levers, sliding clutches connected to the same and adapted to automatically grip the gate, means, substantially as described, for operating said levers, and shifting mechanism for automatically transferring the action from one lever to the other, as and for the purpose set forth.
2. The combination of the gate, a pair of vibrating levers, clutches connected thereto and arranged to automatically grip the gate, a vertical slide-bar, mechanism for operating the same, suitable connections between said bar and the vibrating levers, and mechanism for alternately disconnecting the bar from the levers, substantially as and for the purpose described.
3. The combination of the gate, a pair of bell-crank levers, sliding clutches connected thereto and arranged to automatically grip the gate, a vertical slide-bar, mechanism for operating the same, rods connecting said levers.

vers and said slide-bar, and mechanism for alternately disconnecting said rods from said bar, as and for the purpose set forth.

4. The combination of the gate, a pair of 5 vibrating levers, clutches connected thereto and arranged to automatically grip the gate, a vertical slide-bar, mechanism for operating the same, rods connected to said vibrating levers and adapted to engage said bar, and 10 a rocking arm arranged to throw said rods alternately in and out of engagement with said slide-bar, substantially as and for the purpose described.

5. The combination of the gate, a pair of 15 vibrating levers, clutches connected thereto and arranged to automatically grip the gate, a vertical slide-bar, mechanism for operating the same, rods connected to said vibrating levers and adapted to engage said bar, a rocking 20 lever for throwing said rods alternately in and out of engagement with said slide-bar, and a shifting arm or vane connected to said rocking lever and operated by means of projections on the gate, substantially as described.

6. The combination of the gate, a pair of 25 vibrating levers, clutches connected thereto and arranged to automatically grip the gate, a vertical slide-bar, a plate on the same having 30 depressions in its opposite sides, mechanism for operating said slide, rods connected to said levers and having catches at their upper end arranged to engage the depressions in said slide-bar plate, a rocking lever adapted 35 to engage said rods to alternately free the catches from the depressions in the plate, a shifting arm or vane for operating said rocking lever, and projections on the gate arranged to shift said vane, substantially as 40 described.

7. The combination of the gate, a pair of 45 vibrating levers, clutches connected thereto and arranged to automatically grip the gate, a vertical slide-bar, levers connected to the upper end of the same and extending out over the roadway, having fulcrums on a suitable cross-arm, rods connected to said vibrat-

ing levers, and mechanism for causing said rods to alternately engage said vertical slide-bar, substantially as and for the purpose de- 50 scribed.

8. The combination of the gate, a vibrating 55 lever, a clutch consisting of a sliding band operating on a strip forming part of the gate, suitable connections between said clutch and said vibrating lever, whereby the former is caused to bind upon and grip said strip, and mechanism for operating the lever, substantially as described.

9. The combination of the gate, a vibrating 60 lever, a clutch consisting of a pair of slides operating on a strip forming part of the gate, and a connecting arm or bar rigidly secured to one slide and pivotally connected to the other, a rod connecting said clutch and said 65 vibrating lever, and mechanism for operating said lever, substantially as described.

10. The combination of a gate, a vibrating 70 lever, a clutch arranged on a strip forming part of the gate, and consisting of a pair of 75 encircling bands or boxes and an arm or bar connecting them, being rigidly secured to one band and pivotally connected to the other, a rod connecting said arm and the vibrating lever, and mechanism for operating the latter, substantially as described.

11. The combination, with the gate, of a pair of vibrating levers, clutches operating 80 on a strip forming part of the gate, and each consisting of a pair of sliding bands connected by an arm rigidly secured to one band and pivotally connected to the other, rods connecting said clutches and said vibrating levers, mechanism for operating the latter, and stops against which the pivotal portions of 85 said clutches abut to prevent them from binding on the strip when in their normal positions, substantially as described.

In testimony whereof I affix my signature in presence of two witnesses.

WILLIAM H. COX.
